(57) **CLAIM**

The ornamental design for a graduated rail fence panel, as shown and described.

DESCRIPTION

FIG. 1 is a perspective view of a graduated rail fence panel showing my new design.

FIG. 2 is a right side elevation view of the graduated rail fence panel of FIG. 1, where the left side elevation view is a mirror image thereof.

FIG. 3 is a top plan view of the graduated rail fence panel of FIG. 1.

FIG. 4 is a front elevation view of the graduated rail fence panel of FIG. 1; and,

FIG. 5 is a back elevation view of the graduated rail fence panel of FIG. 1.

The shade lines in the Figures show contour and not surface ornamentation.

The broken lines in the Figures depict environmental subject matter only and form no part of the claimed design.
